UNITED STATES PATENT OFFICE

2,571,572

HOIST FOR REMOVING AND INSTALLING
SPRINGS ON BUSES, TRUCKS, AND THE
LIKE

David L. Harmon, Indianapolis, Ind.

Application March 10, 1947, Serial No. 733,666

6 Claims. (Cl. 214—1)

1

The present invention relates to new and useful improvements in apparatus for removing and installing heavy duty springs on buses, trucks and other vehicles and has for its primary object to provide an apparatus of this character whereby the springs may be removed and installed in a minimum of time and with a minimum of manual effort required.

The invention is designed particularly for the use in removing and installing semi-elliptical type of springs which are extremely heavy and difficult to remove by manually lifting the same and usually require the services of several mechanics for this purpose. Accordingly it is an object of the present invention to provide an apparatus by means of which the spring may be lifted and removed by a single mechanic and including a truck for transporting the spring to a desired location for repairing the same.

A further object of the invention is to provide an apparatus of this character including a truck for handling the spring and by means of which the spring may be turned into any desired position.

A still further object is to provide an apparatus of this character of simple and practical construction, which is efficient and reliable in operation, strong and durable, relatively inexpensive to manufacture and otherwise well adapted for purposes for which the same is intended.

Other objects and advantages reside in the details of construction and operation as more fully hereinafter described and claimed, reference being had to the accompanying drawings forming part hereof, wherein like numerals refer to like parts throughout and in which:

Figure 1 is a side elevational view.

Figure 2 is a top plan view.

Figure 3 is a longitudinal sectional view taken substantially on the line 3—3 of Figure 2.

Figure 4 is a front elevational view, and

Figure 5 is an enlarged sectional view taken on a line 5—5 of Figure 1.

Referring now to the drawings in detail wherein for the purpose of illustration I have disclosed a preferred embodiment of the invention the numeral 5 designates a portable stand which includes a pair of longitudinal spaced parallel frame members 6 converging at their rear ends as shown at 7 for attaching to a platform 8 at the rear end of the stand. A pair of caster or swivelly mounted wheels 9 support the platform 8 at the side edges thereof and similar wheels 10 support the front ends of the frame members 6. A transverse brace 11 connects the frame member 6 intermediate the ends thereof and a trans-

2

verse brace 12 also extends between the converging ends 7 of the frame members.

A mast 13 is pivotally mounted at its lower end for vertical swinging movement on a transverse pin 14 supported at the rear end of the frame member 7 and a jack 15 preferably of a conventional hydraulic type and including a cylinder 16 is pivoted at its lower end for vertical swinging movement on a transverse pin 17 carried by the brace 12. A piston 18 is mounted for working in the cylinder and from which a piston rod 19 extends upwardly through the top of the cylinder and is pivotally connected to a pair of spaced parallel ears 20 by means of a pin 21.

15 A boom 22 projects forwardly of the upper end of the mast 13 and includes a hollow inner end 23 fixed to the upper end of the mast and an outer end 24 rotatably connected to the inner end 23 by a connector 25 having its ends inserted respectively in the adjacent ends of the inner and outer sections 23 and 24 of the boom. The connector is secured to the outer section 24 by bolts or the like 26 and is free in the inner section 23.

20 A worm gear 27 surrounds the connector 25 and suitably secured thereto and with which a worm 28 is operatively engaged for operation by a crank handle 29. The worm is journaled in brackets 30 suitably secured to the inner section 23 of the boom.

25 A head 31 is carried at the outer end of the boom 22 and includes a transverse plate 32 having a pair of rearwardly projecting spaced parallel arms 33 with a pulley wheel 34 positioned therebetween and suitably secured thereto. Trunnions 35 project outwardly from the sides 36 of the arms 33 for pivotally mounting the head in the outer end of the boom 22 for vertical swinging movement of the head.

30 A cable or chain 36 has its front end trained over the pulley 34 and is secured to the underside of the pulley, the cable extending rearwardly of the boom 22 and under a pulley 37 and secured thereto as shown at 38. The pulley 37 is journaled to the boom 22 by trunnions 39 and the ends or flanges 40 of the pulley project rearwardly and provided with a pin 41 to which the upper ends of a jack 42 is pivotally connected and constructed similar to the jack 15. The lower end of the jack is pivoted on a pin 43 carried by a bracket 44 secured to the underside of the boom 22.

35 A transversely extending plate 45 is pivoted at the front surface of the plate 32 of the head by means of a centrally disposed bolt or the like 46.

40 A pair of L-shaped hooks 47 have their upper

ends removably positioned in vertical slots 48 in the plate 45 and are secured in position thereto by laterally extending pins 49 extending through aligned openings 50 and 51 formed respectively in the edges of the plate 50 and in the upper portion of the hooks 47.

A pair of angular clamping members 52 have their inner ends adjustably secured in vertically extending slots 53 formed in the plate 45 and project forwardly of the plate in overlapping relation with respect to the hooks 47.

In the operation of the device the stand is rolled into position at the side of the vehicle from which a spring is to be removed and after the bolts holding the spring to the vehicle have been removed the spring is clamped on the arms 47 by the clamps 52.

By operating the jack 42 the cable 36 is wound on the rear pulley 37 and which in turn rotates the front pulley 34 to swing the head 31 vertically to raise the spring and the boom 22 may also be raised by operating the jack 45 to swing the mast 13 rearwardly.

Also if desired the spring may be rotated on a horizontal axis by rotating the outer section 24 of the boom in the inner section 23 thereof through the operation of the handle 29 and gears 27 and 28. The spring may thus be turned in a desired position for conveniently repairing the spring and the stand may also be moved to a desired location to perform necessary repair work on the spring without requiring the manual lifting or handling thereof.

I claim:

1. A portable hoist of the class described including a frame, a mast pivoted to the frame for vertical swinging movement, a rotatable boom at the upper end of the mast, a work clamping member pivoted to the outer end of the boom for swinging movement on an axis transverse to the axis of the boom, and power means connected to the work clamping member for adjusting the latter on its pivot.

2. A portable hoist of the class described comprising a frame, a mast pivoted to the frame for vertical swinging movement, a boom rotatable on its axis at the upper end of the mast and projecting horizontally therefrom, work clamping means pivoted at the outer end of the boom for vertical swinging movement, individual adjusting means for the mast and work clamping member, and mechanism for rotatably adjusting the boom.

3. A portable hoist of the class described comprising a frame, a mast pivoted to the frame for vertical swinging movement, a boom rotatably

carried at the upper end of the mast and projecting horizontally therefrom, work clamping means pivoted at the outer end of the boom for vertical swinging movement, mechanism for swingably adjusting the mast on its pivot, and pulley and cable winding means connected to the work clamping means to swingably adjust the latter on its pivot.

4. A portable hoist of the class described comprising a frame, a mast pivoted to the frame for vertical swinging movement, a boom rotatably carried at the upper end of the mast and projecting horizontally therefrom, work clamping means pivoted at the outer end of the boom for vertical swinging movement, mechanism for swingably adjusting the mast on its pivot, a pulley journaled on the boom, a jack device connected to the pulley to rotate the latter, and a cable windable on the pulley and connected to the work clamping member to swing the latter on its pivot.

5. A portable hoist of the class described comprising a frame, a mast pivoted to the frame for vertical swinging movement, a boom rotatable on its axis at the upper end of the mast and projecting horizontally therefrom, a work clamping means pivoted at the outer end of the boom for vertical swinging movement, mechanism for swingably adjusting the mast on its pivot, mechanism for rotatably adjusting the boom, and mechanism for swingably adjusting the work supporting member on its pivot.

6. A portable hoist of the class described comprising a frame, a mast pivoted to the frame for vertical swinging movement, a boom rotatably carried at the upper end of the mast and projecting horizontally therefrom, a work supporting head pivoted to the outer end of the boom for vertical swinging movement, and a work clamping member pivoted to the head for vertical swinging movement on an axis at right angles to the axis of the head.

DAVID L. HARMON.
